UNITED STATES PATENT OFFICE.

HERBERT B. TAYLOR, OF ALBANY, NEW YORK, ASSIGNOR TO FEDERAL SIGNAL COMPANY, OF ALBANY, NEW YORK, A CORPORATION.

SYSTEM FOR ELECTRICALLY CONTROLLING AND OPERATING RAILWAY-TRAFFIC-CONTROLLING DEVICES.

1,077,895.

Specification of Letters Patent.

Patented Nov. 4, 1913.

Original application filed August 12, 1910, Serial No. 576,821. Divided and this application filed February 6, 1911. Serial No. 606,717.

To all whom it may concern:

Be it known that I, HERBERT B. TAYLOR, a citizen of the United States of America, residing at 148 Lancaster street, city of Albany, in the county of Albany and State of New York, have invented certain new and useful Improvements in Systems for Electrically Controlling and Operating Railway-Traffic-Controlling Devices, of which the following is a specification.

My invention relates to improvements in systems for electrically controlling and operating railway traffic controlling devices such as signals.

I am aware that railway signals have been electrically controlled and operated prior to this application, but believe that the system employed for control and operation as herein described and illustrated has not before been used. Neither is this specification intended to cover a particular type of signal, but covers a system of control and operation adaptable to any approved signal.

The objects of my improvements are: To provide a more simple and positive means of electrical control. To reduce in number the size of conductors required for the control and operation of the signal. To provide a safe and reliable means of indicating that the signal has returned to its normal position after current is cut off from such signal. To reduce to a minimum the failures which are common to all electrically controlled and operated signals. I attain these objects by the use of the system and various devices as herein described and illustrated by the drawings which accompany this specification, in which:

Figure 1 represents a complete unit for the control and operation of a railway signal of the one arm semaphore type. Fig. 2 represents a controller with its operating lever, lock slide, safety and indication magnet, the lever shown in what is known as the normal position. Figs. 3, 4 and 5 represent the same controller and lever as in Fig. 2, but in the different positions it will occupy when being moved between the normal and reverse position. Fig. 6 shows the core and head of the safety magnet, 20. Fig. 7 shows the core and head of the indication magnet, 21. Fig.

8 is an enlarged view of a portion of a slide bar, 5, with the dogs, 16 and 17, arranged for signal control. Fig. 9 represents the apparatus for producing the inductive indication and is used in connection with signal operating system as shown in Fig. 1. Fig. 10 represents a motor generator as an alternative means of producing the indication and can be employed in place of the apparatus shown in Fig. 9 if desired.

The unit of control and operation as shown in Fig. 1 consists only of such parts as are essential to this description and the claims which follow. 1, represents the bed plate of an interlocking machine, 2, is the operating lever arranged to swing on the spindle, 3, which is suitably mounted on the hanger, 4. A slide bar, 5, is connected with the lever, 2, above the spindle, 3, and arranged to move across the bed plate, 1, when the lever, 2, is operated.

A bell crank, 6, is mounted to swing on a spindle, 7, which is also suitably mounted in a bracket, 8, (see Figs. 2, 3, 4 and 5,) which is attached to the frame of the interlocking machine, not shown. The upper arm, 9, of the crank, 6, is connected to that portion of the lever, 2, which extends below the spindle, 3, by a link, 10. The lower arm, 11, of the crank, 6, is suitably connected with the wiper rod, 12, of the machine controller, 13, shown in Figs. 2, 3, 4 and 5.

In the bed plate, 1, is formed a short recess, 14, and a longer recess, 15, the functions of which will be explained later. A locking dog, 16, and an indication dog, 17, are arranged in the slide bar, 5, in such a manner that they are free to be moved up and down through the said slide bar, 5, into and out of the recesses, 14, and 15, respectively. Directly over the center of the recess, 14, and above and touching the slide, 5, is located a rod, 18, and above the center of the recess, 15, and in like manner is located a rod, 19. These rods, 18, and 19, are suitably secured in position by attachment to the frame of the machine (not shown).

On the bed plate, 1, and directly under the recess, 14, is secured a safety or lock

magnet, 20, (see Figs. 2, 3, 4 and 5), and to the bed plate, 1, under the recess, 15, is similarly secured an indication magnet, 21, (see Figs. 2, 3, 4 and 5). The coil of the safety or lock magnet, 20, is composed of two windings, 22 and 23. The winding, 22, is of about one-tenth ohm resistance and is of large wire of comparatively few turns. The winding, 23, is of about 300 ohms resistance and is of small wire of comparatively many turns. The coil, 24, of the indication magnet, 21, is wound to about 300 ohms resistance with comparatively few turns of a high resistance wire, such as German silver for instance. Through the coil of the safety magnet, 20, passes a core, 25, having secured thereto a head, 26, with lugs or projections, 27 and 27', (see Fig. 6) and through the coil of the indication magnet 20 passes a core, 28, having attached thereto a head, 29.

The rod, 12, of the controller, 13, has mounted thereon and insulated therefrom the wipers, 30, and 31, and also the insulated 25 tripping blocks, 32, 33 and 34. This rod, 12, is arranged to slide in the bearings, 35 and 36, (see Fig. 2.) On the controller panel, 13, are suitably mounted contacts, 37, 37', 38, 38', 39, 39', 40 and 40', also movable 30 contact fingers, 41, 42, 43 and 44, and contacts 41', 42', 43' and 44'.

An electrical source of energy, 45, preferably a storage battery, although a generator would answer as well, is connected with 35 the positive and negative buses, 46 and 47, by wires, 48 and 49. Other buses form part of the controlling machine equipment, 50, being a bus connected with each controller for supplying current to the magnet, 55, 40 and the coil, 54, 51 and 52, being secondary or indication buses. All the buses, 46, 47, 50, 51 and 52, are supposed to extend the entire length of the controlling machine which may be made up of any number of 45 controlling units, the said buses being common to all such units. Between the indication buses, 51 and 52, is connected the indication coil, 53, which is the secondary winding of a suitable induction coil or transformer, as shown in detail in Fig. 9. This secondary winding, 53, is arranged adjacent to a primary winding, 54, which is part of the said induction coil. Another coil, 55, called the contactor coil is adapted, as will 55 be shown, to close a circuit from the battery, 45, through the primary winding, 54, of the induction coil.

The wiring and operation of the controlling and operating devices of the signal will 60 now be described.

As already stated, the source of energy, 45, is connected between the buses, 46 and 47. If the controlling lever, 2, be moved from the position shown in Figs. 1 and 2 to the 65 position shown in Fig. 3, the slide bar, 5,

will be moved forward over the bed plate, 1, the dogs, 16, and 17, which are movably arranged in the slide bar, 5, will be forced downward by the rods, 18 and 19, the dog, 16, will enter the recess, 14, and the dog, 17, will enter the recess, 15. The dog, 17, is beveled on its front edge and is adapted to lift out of the recess, 15, if the slide bar, 5, is moved far enough to permit the beveled edge, 17^a (see Fig. 8) to engage the forward end of the recess, 15. The dog, 16, however, is not beveled on its edge and therefore will not lift out of the recess, 14, but must be forced out by the action of the safety magnet, 20, as will be shown directly. As the 80 lever, 2, is moved as described the controller rod, 12, of the controller, 13, will be moved upward until the various contacts operated by the said rod occupy the position shown in Fig. 3, the wiper, 30, will engage contacts, 37 and 37' and the wiper, 31, will engage contacts, 39 and 39', the movable contact fingers, 41, 42, 43 and 44, will not have been moved. Current from the battery, 45, will now flow from the positive bus, 46, to terminal, 97, wire, 99, to terminal, 100, of the safety magnet, 20; also from terminal, 97, fuse, 96, terminal, 95, wire 94, to terminal, 98, of safety magnet, 20. Current from terminal, 100, passes through the high resistance winding, 23, to terminal, 101, and current from terminal, 98, passes through the low resistance winding, 22, also to terminal, 101. From this terminal current passes over wire, 102, to contact, 38, thence by jumper, 137, to contact 37, wiper, 30, contact 37', wire 141, to contact, 143, of the signal operating mechanism, wiper, 163, contact, 157, wire, 158, field winding, 146, armature, 147, wire, 149, winding, 148, wire, 150, contact, 151, wiper, 164, contact, 145, wire 142, contact, 39, wiper, 31, contact, 39', wire 103, to negative bus, 47. The current flowing in this circuit just described will cause the armature, 147, to revolve and by means of 110 suitable gearing levers, etc., not shown, move the signal blade, 162, to the position shown in the dotted lines. As the signal motor composed of field coil, 146, and armature, 147, becomes energized the coil, 148, which is also in the motor circuit, will attract the armature, 153, against the stop or contact, 155, for a purpose that will be described. As the blade, 162, descends the lever, 160, will be depressed and swing on the pivot, 161, causing the rod, 159, on which are the wipers, 163 and 164, to move upward. As the said rod moves upward the wiper, 164, will disengage the contacts, 151 and 145, opening the circuit at this point. The motor will, however, continue to run owing to the fact that a shunt circuit is made up from contact, 151, wire, 152, armature, 153, contact, 155, wire, 156, to contact, 145. As the blade, 162, reaches the position shown in the 120

dotted lines, the wiper, 163, will disengage the contacts, 157 and 143, and move to the position shown dotted. This will cut off all current from the motor and the coil, 148, 5 permitting the armature, 153, to be pulled away from the contact, 155, by the spring, 154, thus opening the circuit at this point. The only current now flowing from the battery, 45, is from wire, 141, to contact, 143, 10 through slot coil, 165, back to wire, 142. This slot coil will hold the signal in the position to which it has been moved until the controlling lever, 2, is again moved to the position shown in Fig. 1. As current 15 passes over the signal motor operating circuit the safety magnet will become energized and will lift its core, 25, with its head, 26, and force the dog, 16, out of the slot, 14. The core, however, will remain up until the 20 signal motor is cut out by the wiper, 163, disengaging the contacts, 143 and 157.

While the core, 25 is up it will by means of the upwardly projecting lugs, 27 and 27' (see Fig. 6) prevent the slide bar, 5, being 25 moved farther forward than the position in Fig. 3, as the dog, 16', which projects through the slide bar, 5, is arrested by the lugs, 27 and 27'. When, however, the core, 25, drops owing to the diminishing of the flow of current 30 in the signal motor circuit, the lever, 2, and slide bar, 5, can be moved farther forward or to the position shown in Fig. 4. As the lever, 2, is so moved the controller rod, 12, will move upward to the position shown 35 and the tumbler blocks, 33 and 34, will shift the movable fingers, 41, 42, 43 and 44, causing them to pass over the contacts, 41', 42', 43' and 44', respectively; but as the circuits controlled by these contacts are non-operative 40 during this part of the controller movement no current will flow. If it is now desired to put the signal, 162, back to its original or stop position as shown in full lines, the lever, 2, is moved to the position shown 45 in Fig. 5. This movement will move the controller rod, 12, downward, the wiper, 30, will disengage the contacts, 37 and 37', and engage the contacts, 38 and 38', the wiper 31 will disengage the contacts, 39 and 39' and 50 engage the contacts, 40 and 40'. This movement will cut off all current from the signal circuit, deenergizing the slot or hold-clear coil, 165, and permitting the signal to assume the stop position which will put contacts, 55 and 143, into engagement by wiper, 163, and contacts, 151 and 145, into engagement by wiper, 164, as shown in Fig. 1. At the same time the tumbler blocks, 32 and 33, will 55 operate the movable fingers as shown in Fig. 5, closing the indication circuit as follows: Current from battery, 45, will flow to positive bus, 46, through fuse, 96, wire, 118, to bus, 50, wire, 119, contact, 41', finger, 41, wire, 115, finger, 42, contact, 42', wire, 108, 60 terminal, 107, coil of magnet, 55, wire, 109, 65 terminal, 107, coil of magnet, 55, wire, 109,

to negative bus, 47. The current flowing in this circuit will energize the magnet, 55, which will attract its armature against contact, 110, permitting current to flow from terminal, 107, through armature, 56, contact, 70 110, wire, 111, primary coil, 54, wire, 112, to 109, to negative bus. This current will powerfully energize the primary coil, 54, which energization will induce a high electromotive force in the secondary coil, 53. Current 75 from this coil, 53, will now flow to bus, 52, wire, 117, finger, 44, contact 44', wire, 139, contact, 37', wire, 141, contact, 143, wiper, 163, contact, 157, wire, 158, field coil, 146, armature, 147, wire, 149, coil, 148, wire, 150, 80 contact 151, wiper 164, contact 145, wire 142, contact 39, jumper 138, contact 40, wiper 31, contact 40', wire 140, coil 24, of indication magnet, 21, wire 120, contact 43', finger 43, wire 116, bus 51, back to coil 53. The current flowing from this coil, 53, will energize the indication magnet, 21, causing its core, 28, to lift and force the dog, 17, out of the recess, 15, permitting the lever, 2, to be moved to the position shown in Figs. 1 and 90 2. As the lever, 2, is moved to this position the fingers, 41, 42, 43 and 44, will be moved off their respective contacts leaving the indication circuit open.

It will be understood that the above described operations have been performed in proper sequences and with due time intervals allowed for the physical accomplishment of the movements explained—for instance, should the operator move the lever, 2, back to the position shown in Fig. 5 so rapidly as not to give signal, 162, time to close contacts, 157 to 143, and 151 to 145 then the coil, 53, would merely discharge a single impulse of very low amperage through the indication circuit. This current value would be limited by the resistance and inductance of coil, 165, so that there would be no release by means of coil, 24, of indication magnet, 21. In such a case, the operator 100 would have to again reverse lever, 2, to break the circuit to magnet, 55, and then return more slowly to the indicating position of the lever, 2, when if signal, 162, has closed contacts, 157 to 143, and 151 to 145, the coil, 110 24, of indication magnet, 21, will be operated to release the lever, 2, as above described.

The motor generator shown in Fig. 10 can be employed in place of the induction coil shown in Fig. 9, the current to the motor, 120 55^a, being controlled just as is the current through the primary coil, 54, i. e. through the fingers, 41 and 42, and the contacts, 41' and 42'. The generator which delivers the indication current is connected directly 125 across the buses, 51 and 52.

My improvements are particularly set forth in an application for Letters Patent for systems for electrically controlling and operating railway traffic controlling appara- 130

tus, filed August 12th, 1910, Serial No. 576,821, now Patent No. 1,034,167, July 30, 1912, of which this application is a divisional part.

5. What I claim as my invention and desire to secure by Letters Patent, is:

1. In a railway signal controlling system, the combination of a source of energy; a signal and electrical mechanism for moving said signal; two wires leading to the signal mechanism; means for connecting the said two wires to the source of energy to move the signal; means for including the said two wires in a circuit comprising another source of energy of higher potential than the first mentioned source, and an indication magnet in said last mentioned circuit adapted to operate only at the potential of the higher source and not at the potential 20 of the first mentioned source, substantially as described.

2. In a railway signal controlling system, the combination of a prime source of energy; a signal; an electrically operated

device for moving said signal from the stop 25 to the proceed position; a circuit comprising two wires leading from the prime source of energy and including the said device; means controlled by the said device for interrupting the said circuit when the signal 30 has been moved to the proceed position; a secondary source of energy of higher potential than the said prime source; means whereby the said two wires are transferred from the prime source of energy to the secondary source of energy to complete a second circuit, an indication magnet included in said second circuit, the said indication magnet being adapted to become energized at the potential of the secondary source of energy and not at that of the prime source, substantially as described.

In testimony whereof I have affixed my signature in presence of two witnesses.

HERBERT B. TAYLOR.
